UNITED STATES PATENT OFFICE.

HARRY BREGMAN, OF LORAIN, OHIO, ASSIGNOR TO THE STEEL STAMPING COMPANY,
OF LORAIN, OHIO, A CORPORATION OF OHIO.

TOY PISTOL.

Application filed December 23, 1920. Serial No. 432,816.

To all whom it may concern:

Be it known that I, HARRY BREGMAN, a citizen of the United States, residing at Lorain, in the county of Lorain and State 5 of Ohio, have invented certain new and useful Improvements in Toy Pistols, of which the following is a specification.

This invention relates to toy pistols and has for its principal object to provide a 10 simple and inexpensive device, which is capable of producing a series of cracking sounds while pulling a trigger and repeating said sounds when the trigger is automatically returning to its original position.

15 With the above and other objects in view as will be readily understood, the invention will be hereinafter fully described as illustrated in the accompanying drawings, and the novel features thereof will be distinctly 20 pointed out in the appended claims.

In the drawings similar characters are used to designate corresponding parts.

Figure 1 is an elevation of a toy pistol constructed in accordance with my invention, the front half of the body being removed to show the mechanism.

Fig. 2 is a sectional view taken on line 2—2 of Fig. 1.

Fig. 3 is a perspective view illustrating 30 the trigger in cooperative relation with the twisted bar, and

Fig. 4 illustrates the manner of pivotally supporting the twisted bar.

Referring to the drawings 1 represents 35 the body of a toy pistol, which consists of front and rear complementary halves 2 and 3 stamped from sheet metal and secured in matched relation by spot welding at 4 or any other suitable manner. The barrel of

40 the pistol is indicated by 5, the breech portion by 6 and the stock by 7. A sound box 8 formed from stamped material consists of a base 9, sides 10 and 11, and a bottom end 12, and its open top side is closed by a 45 plate of spring material 13, which extends above the upper open end of the box and is held in place by bending thereover the free edges of said sides and bottom end. The base 9 of the sound box 8 is fixed to the inner

50 side of the rear half 3 of the stock 7 by spot welding at 14 or in any other suitable manner, and the free end of the spring plate 13 projects upwardly and is adapted to be en-

gaged by the teeth of a wheel 15, which is arranged crosswise of said spring plate. 55 The toothed wheel 15 is adapted to be rotated first in one direction and then in the other and is fixed to a flat bar 16 having tapering ends 17 and 18, which are supported in openings provided in inwardly 60 extending lugs 19 and 20 struck up from the rear half 3 of the body in alignment with the barrel 5 of the pistol. A portion of the flat bar 16 is twisted as at 21, and this is engaged by the edges of a vertical slot 22 65 provided in a lateral wing 23 of a trigger 24, which is pivoted at 25 to the rear half 3 of the body and its finger portion 26 extends through a slotted opening 27 thereof. By pulling rearwardly upon the finger portion 26 of the trigger, the edges of the slot 22 will act upon the twisted portion of the bar 16, thereby causing the bar and the toothed wheel 15 fixed thereto to rotate in 70 one direction, and a suitable spring 28, having one end attached at 29 to the trigger and its other end connected to a lug 30 stuck in from the rear half of the body of the pistol, is adapted to return the trigger 75 to its original position thus rotating said bar and toothed wheel in the other direction. As the toothed wheel 15 is rotated the free end of the spring plate 13 is forced to one side or the other, and as the teeth of said wheel rotate out of engagement with said free end of the spring plate, the same strikes the next adjacent tooth due to the spring action, thereby producing a sharp report. The full movement of the trigger 80 in either direction rotates the toothed wheel 15 several times, which produces a series of quick cracking sounds.

It is thought that the invention will be fully understood without further explanation, and although the construction illustrated will produce the desired results, it will be understood that slight changes in the design and mechanism may be made within the scope of the claims.

Having fully described my invention, 100 what I claim is:

1. In a toy pistol, the combination of a body, a spring plate, the plate being supported at one end by the body, a toothed wheel for engaging the free end of said plate, 105 means including a trigger and a twisted bar

for rotating the toothed wheel in one direction, and means for returning the trigger to its original position for rotating the toothed wheel in the other direction, substantially as described.

2. In a toy pistol, the combination of a body, a spring plate, the plate being supported at one end by the body, a toothed wheel for engaging the free end of said plate, a bar rotatably supported by the body, the toothed wheel being fixed to the bar, the bar having a twisted portion, and means for acting upon the twisted portion for rotating the bar, substantially as described.

15 3. In a toy pistol, the combination of a body, a spring plate, the plate being supported at one end by the body, a toothed wheel for engaging the free end of said plate, a bar rotatably supported by the body, the toothed wheel being fixed to the bar, a trigger for rotating the bar in one direction, and a spring for returning the trigger to its original position for rotating the bar in the other direction, substantially as described.

20 4. In a toy pistol, the combination of a body, a spring plate, the plate being supported at one end by the body, a toothed wheel for engaging the free end of said plate, a bar rotatably supported by the body, the toothed wheel being fixed to the bar, the bar being twisted, and a trigger acting upon the twisted bar for causing rotation thereof, substantially as described.

25 5. In a toy pistol, the combination of a body, a spring plate, the plate being supported at one end by the body, a toothed wheel for engaging the free end of said plate, a bar rotatably supported by the body, the toothed wheel being fixed to the bar, the bar being twisted, and a trigger acting upon the twisted bar for causing rotation thereof in one direction, and means for returning the trigger to its original position for caus-

ing rotation of the twisted bar in the other direction, substantially as described.

6. In a toy pistol, the combination of a body, a spring plate, the plate being supported at one end by the body, a toothed wheel for engaging the free end of said plate, a bar rotatably supported by the body, the toothed wheel being fixed to the bar, the bar being twisted, a trigger, and the trigger being provided with a slot for receiving the twisted bar to actuate same, substantially as described.

10 7. In a toy pistol, the combination of a body, a spring plate, the plate being supported at one end by the body, a toothed wheel for engaging the free end of said plate, a bar rotatably supported by the body, the toothed wheel being fixed to the bar, the bar being twisted, a trigger, the trigger being provided with a slot for receiving the twisted bar to actuate same, and a spring 60 tending to hold the trigger in its normal position, substantially as described.

15 8. In a toy pistol, the combination of a body, a spring plate, the plate being supported at one end by the body, a toothed wheel for engaging the free end of said plate, a bar, the toothed wheel being fixed to the bar, lugs carried by said body, the lugs being provided with openings, said bar having tapering ends pivotally supported 75 in the openings of said lugs, and means for rotating said bar, substantially as described.

20 9. In a toy pistol, the combination of a body, a sound box supported by the body, a spring plate, the plate being supported at one end by the sound box and forming a side thereof, means for engaging the free end of said plate to cause vibratory movement thereof, and means for actuating said means, substantially as described.

25 In testimony whereof I affix my signature.

HARRY BREGMAN.
